ABSTRACT: Heating values are recovered from sulfur-containing coal in a two-stage process which minimizes pollution. In the first stage, sulfur-containing coal is reacted with CaO in a fluidized bed gasifier which operates adiabatically, under reducing conditions, to yield CaS and a gas rich in CO. The second stage is a conventional boiler to which the off-gas from the first stage and entrained desulfurized coal fines, are delivered as fuel. The flue gas from this boiler contains substantially no sulfur dioxide as a pollutant. CaS is withdrawn from the first stage as a valuable byproduct.

COMBUSTION OF HIGH-SULFUR COAL WITH MINIMAL ECOLOGICAL TRAUMA

PRIOR ART

1. Field of the Invention

Generally, this invention relates to the desulfurization of coal. More particularly, it pertains to a process for the combustion of sulfur-containing coal wherein the sulfur is removed as calcium sulfide.

2. Prior Art

The prior art is legion and it would indeed be presumptuous to attempt a summary herein which would be both comprehensive and objective.

Combustion of coal in fluidized beds is not new. It is shown, for example, in U.S. Pat. No. 3,437,561. Recent work along these lines, done by the British Coal Utilization Research Association, is described in an article by S. Wright et al. "Jl. of the Institute of Fuel" 42, 235-239, June 1969. There have also been prior attempts to recapture the sulfur content of coal, as calcium sulfate, in the course of single-stage combustion of coal in fluidized bed reactors. These were described, variously, by E. B. Robison et al. in "Fluidized Combustion Of Coal For Boiler Capital Cost Reduction And Air Pollution Control" Preprint 45C, A.I. Ch. E., New York (Mar. 1969) and by C. W. Zielke et al. in "Sulfur Removal During Combustion Of Solid Fuels In A Fluidized Bed Of Dolomite" Reprints Am. Chem. Soc., Div. of Fuel Chem., V. 13, No. 4, New York (Sept. 1969). One of the most interesting of the prior art processes is the Winkler process in which fine fuel is gasified in a fixed fluidized bed. This process is discussed in "Industrial and Engineering Chemistry" Vol. 40, No. 4 (Apr. 1948) pg. 562 et seq.

The recent emphasis on preservation of our environment has now made it extremely desirable to obtain heat values from carbonaceous fuels without polluting the atmosphere with sulfur dioxide. While one obvious solution is to utilize fuels which contain little or no sulfur, such fuels are scarce and relatively expensive. Prior art technology, even that devoted to removal of sulfur from carbonaceous fuels, was more concerned with upgrading the quality of the carbonaceous material than with minimizing the ecological trauma associated with its combustion. The treatment or pretreatment of such materials with various sulfur "acceptors" or "getters" is discussed inter alia, in U.S. Pat. Nos. 2,824,047 and 3,387,941. However, in the former, regeneration of the acceptor yields SO_2 and, in the latter, sulfur-derived impurities are released in gaseous form. The general technology of attempts to desulfurize fuels undergoing gasification is reviewed in an article by A. M. Squires in "Preprints," Div. of Fuel Chemistry A.C.S. Vol. 10 No. 4 pg. 20-41 (1966), which discloses, inter alia, the use of dolomite for desulfurization. Said article is incorporated herein by reference.

Suffice it to say that the prior art, while certainly possessed of all the manipulative techniques and equipment technology needed for practice of the instant invention has never produced a two-stage process for combustion of sulfur-containing coal wherein the first stage is a fluidized-bed adiabatic gasifier in which coal is reacted with CaO , which may be derived from limestone or dolomite, under reducing conditions, to produce—not $CaSO_4$ —but rather CaS and wherein the off-gas plus entrained solids are fed as fuel to a conventional boiler whose flue gas is essentially sulfur-free.

SUMMARY OF THE INVENTION

Combustion of sulfur-containing coal is effected in two stages. The first stage is a fluidized bed reactor or gasifier which is operated adiabatically and under reducing conditions. By operating under reducing conditions, formation of $CaSO_4$ and oxides of sulfur is prevented.

The reactor contains a steady-state mixture of presized

limestone (used herein to mean any CaO -yielding material) and coal. Adiabatic conditions are maintained by balancing the exotherm of the oxidation of carbon to CO and the endotherm of calcination of $CaCO_3$ and the heat duty required

5 to heat raw materials to reaction temperatures. Additional control of temperature may be obtained by preheating the fluidizing gas or by the injection into it of water or carbon dioxide. Reactor temperatures range from 1,650° F. to about 2,100° F.

10 Products of the gasifier are both gaseous and solid. CaS is drawn off from the bed as a product from which, if desired, elemental sulfur can be readily recovered. This CaS is relatively free of coal ash since the bulk of the ash is elutriated from the gasifier. The off-gas is rich in CO . Entrained in this gas are fly ash and substantially sulfur-free coal fines from the reactor, which have reached a size where they can no longer be retained in the bed. The second stage is a conventional boiler. The off-gas and entrained solids such as, for example, coal from the reactor are fed directly to it as fuel, preferably 15 isothermally, along with secondary combustion air. The economics of the process are enhanced by maximizing the amount of desulfurized coal solids carried over to the boiler. Flue gas from this boiler consists primarily of CO_2 , H_2O and N_2 . Usual waste heat recovery techniques may be employed 20 for increased thermal efficiency.

Accordingly, it is an object of the invention to provide a method of recovering heat values from sulfur-containing coal which minimizes emission of pollutants, which provides CaS as a byproduct, which is efficient in operation and economically viable.

Other objects of the invention will be apparent to those skilled in the art from a consideration of the description which follows, when read in conjunction with the accompanying drawings.

BRIEF DESCRIPTION OF THE DRAWINGS

In the drawings, wherein like reference numerals designate like parts:

40 FIG. 1 is a schematic flow diagram of one embodiment of the invention.

FIG. 2 is a schematic flow diagram of another embodiment of the invention, differing from that shown in FIG. 1, by virtue 45 of the use of added water in the gasifier.

FIG. 3 is a graph illustrating the minimum CO/CO_2 ratio in the off-gas which must be maintained, at given gasifier temperatures, to produce CaS rather than $CaSO_4$.

50 DESCRIPTION OF THE PREFERRED EMBODIMENTS

Referring now to the FIG. 1, the gasifier, generally 10 is of conventional design. Within it, a grid 11 supports a fluidized bed of coal and limestone 12. A disengagement space 13 is provided above the top of the bed. The gasifier is further provided with a fluidizing gas inlet 14, a solids drawoff 15 and a solids feedline 16.

55 A boiler, generally 20, is provided which includes a combustion chamber 21 and a stack 22, both of conventional design. The overhead effluent from reactor 10 is fed to combustion chamber 21 via transfer line 17. Secondary combustion air is supplied, for example, via line 18 which feeds into the boiler.

Typical operation of the embodiment shown in FIG. 1, is 60 based on 1 ton (i.e. 2,000 pounds) of gasified coal having a sulfur content of 4.5 weight percent with the gasifier operating at a temperature of about 1,840° F. This basis does not include additional coal fines elutriated from the bed. The feed to the bed 12, which enters via line 16, comprises a mixture of coal and limestone totaling about 2,420 pounds. Material enters at ambient temperature (e.g. 77° F.) and its analysis in pounds and pound-moles is as follows:

	0	0-Moles
Coal:		
C	1,600	133
S (as H ₂ S)	93	2.8
H ₂	65	33
Ash	242	2.0 (as Ca ₂ O ₃)
Limestone:	CaCO ₃	420
		4.2
	2,420	175

Air, used as the fluidizing gas, enters through line 14, to provide 64 pound-moles of O₂ and 221 pound-moles of N₂.

The bed 12 itself contains a steady-state mixture of about 90 percent limestone and 10 percent coal. The size of the limestone is adjusted to avoid its excessive elutriation from the bed. Lime carryover is minimal (i.e. below 2 percent of inventory) if particulate lime or lime-yielding material is charged having a size range from 2 to 3 mm. in diameter and the superficial linear gas velocity through the bed is held below 14 ft./second, preferably about 5 ft./second.

The coal is preground so that 99 percent has a size less than 4 mesh. As gasification proceeds, a given particle will be consumed until, ultimately, it leaves through line 17 elutriated in the off-gases. The maximum size of coal particles which will be elutriated is a function of the linear velocity in the bed. Optimum conditions are achieved when the coal has a residence time in the bed just long enough to substantially eliminate its sulfur content and, after this time has elapsed is at elutriable particle size. Carryover of 5-20 percent of coal fines from the gasifier is usual. Greater carryover will, of course, reduce operating costs. However, in this milieu, carryover is limited by the desiderata that: (a) the gasifier temperature be maintained within the range where the desired desulfurization reaction occurs and (b) the sulfur content of the fines is within the generally recognized range for low-sulfur carbonaceous fuels (e.g. less than 1 percent by weight). If these guidelines are followed, carryover is not only nondetrimental but desirable.

Through solids drawoff 15 (which may be in the form of a standpipe exit) there are withdrawn 2.3 pound-moles of CaS and 0.4 pound-moles of ash expressed as CaSiO₃ in addition to some unreacted CaO. Though the material drawn off is primarily CaS and ash, some unreacted coal may also be withdrawn. This coal may, of course, be separated and recycled. The CaS may be utilized, as such, or used as the feed for a process adapted to recover elemental sulfur.

The overhead leaving through line 17 contains entrained coal fines, as stated above, and some CaS despite the presence of disengagement space 13. The gaseous components comprise 136 pound-moles of CO, 35 pound-moles of H₂, 0.2 pound-moles of H₂O, 0.4 pound-moles of CO₂, 221 pound-moles of N₂ and traces of H₂S. This producer gas (i.e. gas rich in CO and H₂) flows at substantially constant temperature to boiler 21 in line 17. Secondary air, which is preferably preheated in conventional equipment enters through line 18. The air supplies 322 pound-moles of N₂ and 86 pound-moles of O₂. Flue gas coming out of stack 22 contains 136 pound-moles of CO₂, 35 pound-moles of H₂O, 563 pound-moles of N₂ and 0.5 pound-moles of SO₂. The process has thus performed as if fuel having 0.8 percent sulfur were conventionally burned whereas the fuel utilized contained, in fact, 4.5 percent sulfur.

The embodiment of the invention shown in FIG. 2 is generally similar to the previous embodiment. It includes, however, a water vaporizer 23, operatively associated with boiler 21. Water flows to this heat exchanger (i.e. vaporizer) through line 24 and exits, as superheated steam through line 25. The steam is added to reactor 10 to help control the exotherm. CO₂ can be used in lieu of or in addition to water for this purpose.

Operating in this manner, the reactor can be run at lower temperatures, on the order of 1650° F. Typical of such an operation, again on the basis of a ton of gasified coal with a sulfur content of 4.5 percent and 9 moles of water fed through line 24 is the following. Feed through line 16:

	0	0-Moles
5	C	1,600
	H ₂ S	93
	H ₂	65
	CaSiO ₃	242
	CaCO ₃	560
		133
		2.8
		33
		2.0
		5.6
10		2,560
		176

Air is supplied through line 14, equal to 61 pound-moles of oxygen and 230 pound-moles of nitrogen. The material withdrawn through line 15 comprises 2.5 pound-moles of CaS and 0.4 pound-moles of CaSiO₃ in addition to some unreacted lime and coal.

In this example the overhead gas, moving through line 17, comprises

	0-Moles
20	
CO	134
H ₂	43
H ₂ O	1.1
CO ₂	2.5
N ₂	230

Flue gas leaving stack 22 under these operating conditions will have the following composition:

	0-Moles
30	
CO ₂	136
H ₂ O	44
N ₂	.563
SO ₂	0.3

The key to the success of the process is the operation of the gasifier under reducing conditions. Such conditions are a function of the ratio of coal to oxygen after steady-state operation has been achieved. This ratio is, in turn, reflected in the CO/CO₂ ratio in the gasifier effluent. Referring to FIG. 3, operation should always be above the line to maintain reducing conditions in the gasifier. Accordingly, feed of air and coal must be adjusted so that the CO/CO₂ ratio is represented by a point on or above the line in FIG. 3.

The limestone utilized is always in excess of that necessary to supply CaO to react with the sulfur in the coal. Molar excesses of 50 to 200 percent are preferable, with an optimum range of 75 to 150 percent.

While two embodiments of the invention have been described, many modifications and variations will be apparent to those knowledgeable with respect to the design and operation of fluidized-bed gasifiers. Accordingly, the scope of the invention is to be limited only by a reasonable interpretation of the appended claims.

I claim:

1. A process for recovering heat values from sulfur-containing coal while minimizing the yield of sulfur dioxide, comprising the steps of:
  - a. establishing a bed or particulate coal and limestone;
  - b. fluidizing said bed with a stream of air containing enough oxygen to produce CO from the coal;
  - c. feeding said bed, below the top thereof, with fluidizable-size sulfur-containing coal;
  - d. feeding said bed with an amount of limestone in excess of that needed to produce CaS from the sulfur contained in the coal;
  - e. reacting carbon with oxygen in said bed, under adiabatic conditions, in a temperature range of from about 1650° F. to about 2100° F.;
  - f. adjusting the feed of air and coal to prevent oxidation of CaS to CaSO₄ by producing a reducing environment in

- the bed, as reflected by the CO/CO₂ ratio in the gaseous effluent therefrom, said ratio having a value above the minimum represented by the curve in FIG. 3;
- g. drawing off particulate CaS from the bed;
  - h. removing from the bed, as an overhead effluent, producer gas in which is entrained a quantity of fine coal, said fine coal having a sulfur content substantially less than that of the coal originally fed;
  - i. transferring said producer gas and its entrained solids to the inlet of a boiler;
  - j. burning said producer gas and said entrained coal, with the addition of secondary air, in said boiler to recover the heat value thereof;
- whereby the stack gas emitted from said boiler will contain less SO₂ than it would, had the original coal been fed directly thereto.
2. The process of claim 1 wherein the amount of limestone fed contains from 50 to 200 mol percent excess of Ca.
  3. The process of claim 1 wherein 99 percent of the coal fed

- to the bed has a size less than 4 mesh.
4. The process of claim 1 wherein the producer gas is transferred to the boiler isothermally.
  5. The process of claim 1 where a fluid selected from the group consisting of water and CO₂ is added to the fluidized bed to control the exotherm thereof.
  6. The process of claim 2 wherein 99 percent of the coal fed to the bed has a size less than 4 mesh.
  7. The process of claim 2 wherein the producer gas is transferred to the boiler isothermally.
  8. The process of claim 2 wherein a fluid selected from the group consisting of water and CO₂ is added to the fluidized bed to control the exotherm thereof.
  9. The process of claim 3 wherein a fluid selected from the group consisting of water and CO₂ is added to the fluidized bed to control the exotherm thereof.
  10. The process of claim 9 wherein the producer gas is transferred to the boiler isothermally.

UNITED STATES PATENT OFFICE
CERTIFICATE OF CORRECTIONPatent No. 3,599,610 Dated August 17, 1971Inventor(s) Marshall L. Spector

It is certified that error appears in the above-identified patent and that said Letters Patent are hereby corrected as shown below:

Column 2, line 17, after "bed". Start a new paragraph.

Column 3, line 1, delete "0" and substitute --Pound--

Column 3, line 1, delete "0-Moles" and substitute --Pound-Moles--

Column 3, line 4, insert parenthesis after "(as H₂S"

Column 3, line 6, after "O₃" insert parenthesis

Column 4, line 1, delete "0" and substitute --Pounds--

Column 4, line 1, delete "0-Moles" and substitute --Pound-Moles--

Column 4, line 20, delete "0-Moles" and substitute --Pound-Moles--

Column 4, line 31, delete "0-Moles" and substitute --Pound-Moles--

Signed and sealed this 9th day of May 1972.
